UNITED STATES PATENT OFFICE.

WERNER O. OLSON, OF EAST ORANGE, NEW JERSEY, ASSIGNOR TO ASHER MANUFACTURING COMPANY, OF IRVINGTON, NEW JERSEY, A CORPORATION OF DELAWARE.

SUPPLY DOOR FOR WASH WHEELS.

Application filed March 23, 1925. Serial No. 17,748.

This invention relates to supply doors for wash wheels or as they are more commonly known, washing machines of the type wherein a pair of coaxial horizontal cylinders are provided, the outer one being stationary and the inner one rotatable or oscillatable therein.

It is a general object of this invention to provide a novel and improved supply door for wash wheels.

More particularly it is an object of this invention to provide a supply door for wash wheels which is self-washing, that is, has its inner surface when closed exposed to the spray of the liquid within the outer cylinder.

Another object of the present invention consists in the provision of a supply door for wash wheels arranged on a horizontal axis intermediate its circumferential width in order that when open, the lower portion may project a material distance within the outer cylinder or drum to prevent supply materials from falling on the edge of the main door opening.

Still another object of the present invention consists in the provision of a supply door for wash wheels which will remain both open and closed without the use of weights, springs, latches or other holding means.

A further object of the present invention consists in the provision of a supply door for wash wheels which is associated with a handle bar which is to be normally used for opening and closing the main door of the outer cylinder.

In the accompanying drawing and following specification there is disclosed by way of example only, a single embodiment of the present invention, but it is to be understood that various changes and modifications may be made therein by those skilled in the art, in the size, shape, arrangement, proportion and location of the various parts without departing from the spirit or scope of the invention as set forth in the appended claims.

In said drawings:

Fig. 1 is a front elevation of a wash wheel provided with supply doors con-

structed in accordance with the present invention; and

Fig. 2 is a partial transverse section thereof on line 2—2 of Figure 1.

Wash wheels or washing machines of the larger sizes, such as the power driven types used in laundries, commonly comprise a horizontal stationary outer cylinder or drum and a central inner cylinder or drum journaled for rotation or oscillation therein under the action of a suitable source of power. The inner cylinder is usually perforated and the outer cylinder is adapted to be watertight and contain a supply of water and washing materials, in which the clothing to be washed is agitated by means of the movable inner cylinder in which it is contained. The outer cylinder is provided, in most cases, with large sliding doors to gain access to the doors in the inner cylinder in order to fill and empty it. During the washing process it becomes necessary to add soap, washing powder and later bluing to the water contained in the outer drum or cylinder, and since this water is being splashed and agitated considerably, it is not advisable to open the larger doors, and it has therefore been proposed to provide in these doors supply openings of various sorts through which these materials may be introduced while the inner cylinder remains in motion. It is often the case that safety devices are required or provided which necessitate the stopping of the inner cylinder before the large doors can be opened. The present invention contemplates the provision of a novel supply door which will best be understood by reference to the accompanying drawing.

In the drawings, illustrative of a well known type of wash wheel, 10 represents the stationary outer cylinder formed of any suitable material, but as here shown, composed of wooden stays 11 suitably banded together as at 12 and provided with any desirable form of supporting means, such as the feet 13. Within this outer or stationary cylinder is mounted for rotation or oscillation, in any desirable manner, (not shown) the inner cylinder or drum 14, also preferably formed of wood. In the particular ma-

chine disclosed, there are provided two large sliding doors 15 and 16 which are formed of thin sheet metal curved to conform to the shape of the drum and sliding circumferentially of the drum between the band 12 and the end bands or guides such as 17.

Each of the large or main doors 15 and 16 is provided with a supply door or shutter such as 18 formed of sheet metal of substantially the same thickness as that of the main door. The supply door operates in a substantially rectangular opening in the main door, reinforced at the top by a bar 19 and at the bottom by a bar 20. To additionally 10 strengthen the lower edge of the door which is somewhat weakened by having the metal removed from this opening, the angle bar 21 has one of its arms secured to the inner face near the lower edge of the door with 15 the other arm projecting laterally inward to form an abutment which engages against the metal lining 22 of the opening in the outer drum 10, as best shown in Figure 2, and forms a stop to limit the movement of 20 the large door to closed position. The lower edge of the door projects slightly over the lining, as shown at 23, to form a watertight joint.

The circumferential edges of the supply 30 door opening are reinforced by the bases or feet 24 of the handle bar brackets 25, which feet extend the full length of these circumferential edges and are securely riveted to the metal of the main door. They support 35 between them and above the surface of the door, the handle bar 26 which can conveniently be grasped by the operator for opening and closing the main door. This handle bar is preferably made in channel form, as 40 shown best in Figure 2, and is fastened by any desirable means to the vertical sectors 27 projecting from the bases 24 of the brackets. These brackets are provided near the surface of the main door with the bosses 45 28 adapted to receive the hinge pins 29 of the supply door which are firmly secured in the blocks 30 riveted or otherwise secured to the supply door at a point intermediate its circumferential width.

50 The hinge pins are so positioned on the supply door that its lower end projects within and its upper end without the main door, as shown in full lines in Figure 2, so that when in its closed position the lower 55 end abuts against and inside the lower end of the main door where it is reinforced by bar 20 and forms a watertight fit by this overlap, whereas the upper end of the supply door overlaps, on the outside, the material of the main door adjacent its reinforcing bar 19, thus providing a tight fit at this 60 point. The sectors 27 of the brackets fit closely against the ends of the supply door and insure that any leakage which may take 65 place around these ends will be drained back

into the drum. When open the door assumes the position shown in dotted lines in Figure 2, and its upper edge fits within the rabbet 31 in the upper edge of the channel handle bar 26 which thus limits the amount 70 of its opening. In a number of cities the safety code provides that the opening shall be so small that the operator cannot place his hand within it. This is positively assured by the substantial handle bar 26 which 75 forms an effective stop for the supply door. It may be found desirable to provide a handle or knob 32 for convenience in opening and closing the supply door.

It will be observed by the dotted line position of the door when opened, that the lower edge 33 projects a substantial distance within the drum and prevents any material, which is introduced through the opening, from dropping upon the reinforcing strip 22 and accumulating there. When the door is closed its position is inverted so that any material which may have stuck to it will fall off, and since the door forms a part of the main door and conforms to its curvature, 80 it is subjected to the spray and splashing of the liquid within the outer drum whose level is, of course, below that of the lower edge of the main door, so that its inner surface will be well washed and none of the 85 washing compounds will stick to it. These two last mentioned features are of considerable importance for it is found that certain of the chemicals used in the washing process neutralize each other, if they become mixed. 90 For instance, it has been found that a large part of the bluing introduced into the drum, into fresh water of course, will be neutralized by any of the soap or alkaline washing compounds which may stick to the inner face 95 of the supply door or lodge upon the upper edge 22 of the opening in the drum. The position of the hinge pins 29 of the supply door is such that when in the open or closed position, its center of gravity is lower than when it passes vertically over the hinge pins 100 so that it will therefore remain either in the open or closed position without the assistance of any springs, latches, weights or other holding means. The sectors 27 close 105 the ends of what may be considered a hopper, when the door is open, for convenience in filling and prevent the washing materials from being spilled around the ends of the door.

110 Another feature of advantage of the present invention is that it can be made in various sizes without any special constructional difficulties since the same end brackets which include the sectors 27, supports for the handle bar 26, and the bosses for the hinge pins 29 can be used for any length supply door opening, the only change necessary being in the length of the handle bar and in the door member, each of which being made of 115 120 125 130

fabricated material can be readily cut to length.

Having thus described the invention what is claimed as new and desired to be secured by Letters Patent is:

1. In a wash wheel, in combination a drum having an opening therein, a main door slideable to close said opening and having a supply opening therein, a shutter for said supply opening and means pivoting said shutter to said door intermediate the length of said shutter whereby the lower edge thereof protrudes through said supply opening when said shutter is opened. 70
2. In a wash wheel, in combination an outer casing having an opening therein, a main door adapted to close said opening and having a supply opening therein in an inclined surface, a shutter pivoted on a horizontal axis to close said supply opening, pivots for said shutter below the center of gravity thereof but above the bottom, whereby said shutter will remain open or closed, the lower edge of the shutter being within and the upper edge without the main door at all times. 75
3. In a wash wheel in combination, an outer horizontal cylinder having a filling opening above the horizontal center thereof, a main door slideable circumferentially to close said opening and having a supply opening therein, a shutter fitting through said opening, means pivoting said shutter to said door on a horizontal axis intermediate the circumferential height thereof, said pivot means being so positioned that said shutter will remain open or closed by gravity. 80
4. In a wash wheel in combination, a relatively thick, outer, horizontal cylinder having an opening above the horizontal center thereof, a relatively thin main door slideable circumferentially on the outside of said cylinder to close said opening and having a supply opening therein, a supply door adapted to close said opening, said door being pivoted to the main door on a horizontal axis above the lower edge of said supply door, whereby upon opening said lower edge will enter said supply opening and extend above and over the lower edge of the opening in the main cylinder for the purpose described. 85
5. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, a handle bar for use in operating said main door, said handle bar extending parallel to said shutter and serving as a stop to limit its opening. 90
6. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, reinforcing means for the edges of the supply opening, said pivot means for said shutter being so positioned that the upper edge of the shutter overlaps the outside of said door and 95
7. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, a handle bar for use in operating said main door, said handle bar extending parallel to said shutter and serving as a stop to limit its opening, brackets supporting said handle bar from said main door and bases thereon reinforcing the edges of said supply opening. 100
8. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, a handle bar for use in operating said main door, said handle bar so spaced from said door as to form a limiting stop for the upper edge of said shutter. 105
9. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, brackets mounted on said door at the ends of said supply opening, pivots for said shutter carried by said brackets and vertical sectors on said brackets forming with said shutter, when open, a hopper leading to said supply opening. 110
10. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, reinforcing means for the edges of the supply opening, said pivot means for said shutter being so positioned that the upper edge of the shutter overlaps the outside of said door and 115
11. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, reinforcing means for the edges of the supply opening, said pivot means for said shutter being so positioned that the upper edge of the shutter overlaps the outside of said door and 120
12. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, reinforcing means for the edges of the supply opening, said pivot means for said shutter being so positioned that the upper edge of the shutter overlaps the outside of said door and 125
13. In a wash wheel, in combination, an outer horizontal cylinder having a filling opening above the horizontal center thereof, a main door slideable circumferentially to close said opening and having a supply opening therein, a shutter for said supply opening pivoted to said main door below the center of gravity of said shutter, reinforcing means for the edges of the supply opening, said pivot means for said shutter being so positioned that the upper edge of the shutter overlaps the outside of said door and 130

the lower edge the inside to form a water tight joint.

11. In a wash wheel, in combination, an outer horizontal cylinder having a filling opening above the horizontal center thereof, a main door slidable circumferentially to close said opening and having a supply opening therein, a shutter for said supply opening pivoted to said main door below the center of gravity of said shutter, rein-

forcing means for the edges of the supply opening, said pivot means for said shutter being so positioned that the upper edge of the shutter overlaps the outside of said door and the lower edge the inside adjacent said reinforcements.

In testimony whereof I hereunto affix my signature.

WERNER O. OLSON.
